GRINDING MACHINE

John I. Garside, West Boylston, Mass., assignor
to Norton Company, Worcester, Mass., a cor-
poration of Massachusetts

Application December 7, 1939, Serial No. 308,035

12 Claims. (Cl. 51—95)

The invention relates to grinding machines, and more particularly to a grinding machine for accurately grinding a helical groove on a work piece.

One object of the invention is to provide a simple and thoroughly practical grinding machine for grinding a helical groove on a work piece. Another object of the invention is to provide a grinding machine for grinding a helical groove which is automatic in operation from the time the operator has placed a work piece in position until the grinding operation is finished. Another object of the invention is to provide a universal mounting for the grinding wheel whereby the grinding wheel and its supporting spindle may be swivelled about a horizontal and also about a vertical axis to position the grinding wheel for producing the desired helical groove on a work piece.

Another object of the invention is to provide a work driving and table traversing mechanism which are synchronously driven so that the rotation and traverse of the work piece are coordinated. A further object of the invention is to provide a two-speed work drive mechanism whereby the work may be rotated and the table traversed at proper speeds for a grinding operation when the table is traversed in one direction and the table may be traversed at a rapid rate during the return traverse while the wheel is out of operative engagement with the work piece. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is illustrated one of many possible embodiments of the mechanical features of this invention,

Fig. 1 is a front elevation, having parts broken away and shown in section, of the improved helix grinding machine;

Fig. 2 is a right-hand end elevation of the machine, on an enlarged scale, having parts broken away and shown in section;

Fig. 3 is a fluid pressure and electric wiring diagram of the operating mechanisms of the machine;

Fig. 4 is a longitudinal sectional view, on an enlarged scale, through a portion of the wheel slide;

Fig. 5 is a fragmentary front elevation, on an

enlarged scale, of the wheel feeding mechanism;

Fig. 6 is a fragmentary vertical sectional view, on a slightly reduced scale, taken approximately on the line 6—6 of Fig. 5;

Fig. 7 is a fragmentary sectional view, taken approximately on the line 7—7 of Fig. 5;

Fig. 8 is a fragmentary cross-sectional view, on an enlarged scale, through the headstock, taken approximately on the line 8—8 of Fig. 1;

Fig. 9 is a longitudinal sectional view, taken approximately on the line 9—9 of Fig. 8;

Fig. 10 is a left-hand end elevation of the headstock as shown in Fig. 9;

Fig. 11 is a horizontal sectional view, taken approximately on the line 11—11 of Fig. 10;

Fig. 12 is a fragmentary rear elevation of the wheel feeding mechanism, taken approximately on the line 12—12 of Fig. 2;

Fig. 13 is a fragmentary cross-sectional view, on an enlarged scale, of the manually operable table positioning or traversing mechanism, taken approximately on the line 13—13 of Fig. 1;

Fig. 14 is a fragmentary plan view showing the relative positions of the grinding wheel and the work piece;

Fig. 15 is a fragmentary plan view of the wheel slide, showing the vertical pivot therefor and the horizontal angular adjusting mechanism; and

Fig. 16 is a longitudinal sectional view, taken approximately on the line 16—16 of Fig. 13.

A helix grinding machine has been illustrated in the drawings comprising a base 10 which supports a longitudinally traversable work supporting table 16 on the usual V-way 17 and flat way 18 which are formed on the upper surface of the base 10. The table 16 supports a swivel table 19 which is arranged to swivel about a stud 20 which is fixed relative to the table 16.

A grinding wheel 25 is supported at one end of a rotatable spindle 26 which is journalled in suitable bearings in a wheel slide 27. The grinding wheel 25 and its supporting spindle 26 may be rotated in any suitable manner such as, for example, an electric motor 28 mounted on the

upper surface of the wheel slide 27. The motor 28 is provided with a pulley 29 which is connected by means of a driving belt 30 with a pulley 31 mounted on the opposite end of the wheel spindle 26.

The wheel slide 27 is supported on a transversely movable slide 32 which is arranged to move transversely on a V-way 33 and a flat way 34 formed on a wheel slide base member 35. The wheel slide 27 is preferably pivotally connected to the cross slide 32 so that the axis of the grind-

ing wheel spindle 26 may be adjusted in a vertical plane so that it lies at an angle to the axis of the work piece being ground. The cross slide 32 is provided with integrally formed brackets 36, only one of which has been shown in Fig. 4, which support a rock shaft 37. The wheel slide member 27 is provided with outwardly extending bosses 38 which are journaled on the pivot shaft 37 so that the wheel slide 27 may be rocked relative to the shaft 37. The rock shaft 37 is preferably arranged in a horizontal position so that the wheel spindle 26 may be adjusted in a vertical plane into the desired angular position relative to the axis of a work piece being ground.

To facilitate adjustment of the wheel slide 27 relative to the cross slide 32, a pair of adjusting screws 40 and 41 (Fig. 2) pass through screw threaded apertures in the wheel slide 27 and have their ends bearing against upper plane surfaces on the bosses 42 and 43, respectively, formed on the upper surface of the cross slide 32. A pair of lock nuts 44 and 45 are provided to lock the adjusting screws 40 and 41, respectively, in their adjusted position.

To facilitate accurate adjustment of the slide 27 relative to the cross slide 32, the cross slide 27 is provided with a pair of outwardly extending brackets 46 and 47 which serve as a support for a sleeve 48 through which passes a rod 49. The rod 49 passes through elongated slots 50 and 51, respectively, which are formed in brackets 52 and 53. The brackets 52 and 53 are fixedly mounted on the cross slide 32. A pair of nuts 54 and 55 are screw threaded onto the rod 49 and serve to clamp the rod 49 and the sleeve 48 in adjusted position to hold the slide 27 in its adjusted position during a grinding operation.

The cross slide 32 is provided with an outwardly projecting portion 58 having a guide block 59 fixedly secured thereon. A gauge block 60, such as the well known Johansson gauge block, of the required thickness may be moved into position in a groove formed in the block 59, which serves precisely to locate the sleeve 48 in a position to locate the axis of the wheel in the desired angular position relative to the axis of the work piece being ground. After this adjustment has been made, the clamping nuts 54 and 55 may be tightened to lock the slide 27 in adjusted position. The angular position of the wheel spindle 26 is determined by the lead of the helix being ground. Raising the sleeve 48 by placing a gauge block 60 of the required thickness, the wheel spindle 26 may be accurately positioned as desired.

In grinding a helical path, such as that shown in Fig. 14, it is desirable to provide a pivotal adjustment for the grinding wheel whereby the axis of the wheel spindle 26 may be adjusted angularly in a horizontal plane. In order to provide such an adjustment, the wheel slide base 35 is preferably pivotally connected to the base 15 by means of a vertically arranged pivot stud 62 (Figs. 2, 3 and 13). To facilitate angular adjustment of the wheel slide base 35, the machine base 15 is provided with two fixed upwardly extending brackets 63 and 64 (Fig. 15) which are provided with adjusting screws 65 and 66, respectively. The wheel slide base 35 is provided with an index pointer 67 and the base 15 of the machine is provided with a graduated scale 68. By manipulation of the adjusting screws 65 and 66, respectively, the wheel slide base 35 may be swivelled about the pivot stud 62 in a horizontal plane to produce the desired

horizontal angular position of the wheel spindle 26.

Wheel feed

5 A wheel feeding mechanism is provided to move the grinding wheel 25 and its supporting slide 27 together with the cross slide 32 transversely to produce the desired grinding action. In order to facilitate a horizontal angular adjustment of the wheel slide base 35, the wheel feeding mechanism is preferably supported by the wheel slide base 35 so that the mechanism is always maintained in a predetermined relationship with the cross slide 32.

15 The cross slide 32 supporting the wheel slide 27 is provided with a depending half nut 70 which meshes with or engages a rotatable cross feed screw 71 journaled in a slidably mounted bearing 72 at one end and a bearing 73 (Fig. 2) 20 at the other end. The bearings 72 and 73 are supported on the wheel slide base 35 and arranged to swivel therewith when the base 35 is adjusted angularly. The forward end of the feed screw 71 is slidably keyed to a rotatable sleeve 74 which supports a gear 75. The gear 75 meshes with a gear 76 supported by a rotatable shaft 77 which is journaled in bearings 78 and 79 which are supported by the wheel slide base 35.

25 The feed screw 71 is arranged to be rotated by means of a manually operable feed wheel 80 which is supported on the end of a rotatable shaft 81 which is in turn supported by a bracket 82 fixedly mounted on the front of the base 15. The shaft 81 carries a gear 83 which meshes 30 with a gear 84. The gear 84 is supported on the forward end of a rotatable shaft 85 journaled in a suitable bearing within the housing 86 which is fixedly mounted on the base 15. To facilitate a feeding movement in any angular 35 adjustment of the wheel slide base 35, a universal driving connection is provided between the shaft 77 and the shaft 85. A universal joint 87 is mounted on the forward end of the shaft 77 and a universal joint 88 is mounted on the inner end 40 of the shaft 85. The universal joints 87 and 88 are connected by a telescopic drive shaft 89. It will be readily apparent from the foregoing disclosure that a rotary movement of the manually 45 operable feed wheel 80 will be transmitted through the mechanism above described to rotate the feed screw 71 to produce a transverse feeding movement of the cross slide 32 in any 50 adjusted angular position of the wheel slide base 35. The feed screw 71 may be rotated by a 55 manual operation of the feed wheel 80 or it may be intermittently fed by a pawl and ratchet feed mechanism to be hereinafter described.

In order that the wheel slide 27 and its supporting cross slide 32 may be moved rapidly toward and from a grinding position automatically, the feed screw 71 is connected through the slidably mounted, non-rotatable bearing member 72 with one end of a piston rod 92. A fluid pressure cylinder 93 is arranged in axial alignment with the feed screw 71 and is also supported on the wheel slide base 35. The cylinder 93 contains a slidably mounted piston 94 which is connected with the piston rod 92. A fluid pressure pump 95 which is driven by an electric 60 motor or other suitable drive (not shown) serves to pump fluid through a pipe 96 from a reservoir 97 formed within the base 15. The pump 95 forces fluid under pressure through a pipe 98 to a main control or feed control valve 99.

65 The main control valve 99 is preferably of a

piston type comprising a valve stem 100 having formed integrally therewith a plurality of valve pistons 101, 102, 103 and 104 which form a plurality of valve chambers therebetween. In the position of the valve 99 (Fig. 2), fluid under pressure passing through the pipe 98 enters a valve chamber located between the valve pistons 102 and 103 and passes out through a passage 105 into a cylinder chamber 106 to cause the piston 94 to move rapidly toward the right (Fig. 2) to cause a rearward movement of the cross slide 32 together with the wheel slide 27 and the grinding wheel 25. During the passage of fluid under pressure into the cylinder chamber 106, fluid is exhausted from a cylinder chamber 107, through a passage 108, into a valve chamber located between the valve pistons 101 and 102, respectively, and out through a pipe 109 which exhausts into the reservoir 97. A speed control or throttle valve 90 (Fig. 2) is provided in the pipe line 109 by means of which the speed of movement of the piston 94, the cross slide 32 and the grinding wheel 25 may be regulated as desired.

The valve stem 100 is normally held in a rearward feeding position (Fig. 2) by means of a spring 110. An electric solenoid 111 is provided to shift the valve stem 100 toward the left (Fig. 2) into a forward feeding position. The solenoid 111 is connected by means of a link 112 and a stud 113 to the lower end of a pivotally mounted lever 114. The lever 114 is pivotally supported by means of a stud 115 which is carried by a bracket 116 fixedly mounted relative to the base 15. The upper end of the lever 114 is operatively connected to a valve actuating rod 117. To facilitate actuation of the valve 99 in any position of the wheel slide base 35, a universal joint 118 is provided between the rod 117 and the valve stem 100. It will be readily apparent from the foregoing disclosure that when the solenoid 111 is energized, the lever 114 will be rocked in a counterclockwise direction to move the valve stem 100 toward the left (Fig. 2) so that fluid under pressure passing through the pipe 98 into the valve chamber between the valve pistons 102 and 103 will pass through the passage 108 into the cylinder chamber 107 to produce a forward feeding movement of the piston 94 and the feed screw 71 which in turn transmits a forward feeding movement through the half nut 70 to the cross slide 32, the wheel slide 27 and the grinding wheel 25.

Dash pot—Feed control

The piston and cylinder mechanism above described serves to cause the grinding wheel 25 rapidly to approach or recede from the work piece. In order to reduce the rapid approaching movement to a predetermined grinding feed, it is desirable to provide a wheel feed regulator or controlling mechanism, such as a dash pot mechanism, which may be rendered effective when the grinding wheel 25 is about to contact with the surface of the work piece being ground. As illustrated in Fig. 2, an outwardly projecting casing 120 is fixedly mounted on the head of the cylinder 93 and contains a pair of diametrically spaced dash pot pistons 121 and 122. The dash pot pistons 121 and 122 are normally held in a rearward position by means of springs. During the rapid approach of the grinding wheel 25, the dash pot pistons are inoperative.

The piston rod 92 extends toward the rear of the machine and is provided at its outer end with

a sleeve 123 which may be adjusted longitudinally relative to the extended portion of the piston rod 92. The parts are so arranged that the sleeve 123 moves rearwardly when the piston rod 92 moves toward the rear. The dash pot pistons 121 and 122 are limited in their rearward movement by means of a flanged plate 124 which is supported on one end of the sleeve 123. An adjusting screw 125 serves to limit the rearward movement of the plate 124 and thus serves to limit the rearward movement of the dash pot pistons 121 and 122 under the influence of their respective springs.

When fluid under pressure is admitted to the cylinder chamber 107 to cause the grinding wheel 25 to move toward the work piece, the rapid approaching movement thereof continues until the sleeve 123 picks up the plate 124, which engages the ends of the dash pot pistons 121 and 122, respectively. The continued movement of the piston 94 toward the left (Fig. 2) is resisted by the dash pot pistons 121 and 122, respectively, which force fluid under pressure from the dash pot chambers 126 and 127 into a reservoir 128. The dash pot chambers 126 and 127 are preferably interconnected with each other and are arranged to exhaust fluid therefrom through a needle valve 129 or an adjustable throttle valve 130 into the reservoir 128. The throttle valve 130 is preferably located on the front of the machine base so that it may be readily adjusted from the operator's control station.

Positive stop

In order to grind a work piece to a predetermined size, it is necessary to feed the grinding wheel 25 toward the work piece to grind the same and then to stop the infeed and allow the grinding wheel to grind out or allow the sparks to die out in order to round up the surface of the work piece to a predetermined shape and size. As illustrated in Fig. 2, the forward movement of the piston rod 92 causes a rapid approaching movement until the sleeve 123 picks up the dash pot pistons 121 and 122 to cause a slow infeed which continues until an adjustable collar 131 adjustably supported on the sleeve 123 engages a fixed surface 132 on the rear of the casing 120, thereby positively limiting the infeeding movement of the grinding wheel 25 and causing the wheel to dwell in contact with the work during the finish grinding period. The adjustable stop collar 131 surrounds the sleeve 123 and is held in adjusted position thereon by means of lock nuts 133.

The throttle valve 130 is connected by a pipe 135 with the reservoir 128. The pipe 135 also connects the reservoir 128 to a ball check valve 136 which remains closed during the forward feeding movement of the grinding wheel but which opens upon the rearward movement of the grinding wheel 25 as the dash pot pistons 121 and 122 move to a rearward position to allow quick return of fluid to the dash pot chambers 126 and 127, respectively.

The dash pot mechanism is normally an independent fluid mechanism during the normal operation of the machine. In order readily to fill the reservoir 128 to maintain the desired quantity of fluid therein, a pipe 137 is connected between the pump 95 and the reservoir 128. A valve 138 is located in the pipe line 137 to control the flow of fluid therethrough. An overflow pipe 139 is connected between the vertically extending portion of the reservoir and the main

reservoir 97 within the base 15 of the machine so that in case the fluid within the reservoir 128 rises above the desired level, the excess fluid will return directly to the reservoir within the base of the machine.

Ordinarily the valve 138 is manually opened when it is desired to fill the reservoir 128 and then remains closed during the normal operation of the machine. If desired, however, in order to insure the fluid level within the reservoir 128 at all times, the valve 138 may be opened partially so that there will be a continuous flow of fluid into the reservoir 128, and in this case the overflow pipe 139 serves to prevent the fluid level in the reservoir 128 rising above the desired point.

Automatic infeed

It is desirable to provide a suitable automatic infeeding movement of the grinding wheel 25 which operates in timed relation with the traversing movement of the table 16. In the preferred form a table actuated pawl and ratchet mechanism is provided comprising a ratchet wheel 145 (Figs. 6 and 7) which is fixedly mounted to rotate with the feed wheel 80. An oscillatable pawl carrying member 146 is rotatably supported on a hub portion 147 of the ratchet wheel 145. The pawl carrying member 146 supports a pivotally mounted pawl 148 on a stud 149 which is fixed to the pawl carrying plate 146. The pawl carrying plate 146 is provided with a downwardly extending arm 150 which is connected by means of a stud 151 with a link 152. The other end of the link 152 is connected by means of a stud 153 with a lever 154. The lever 154 is fixedly mounted on the end of a rock shaft 155 which is rotatably supported in a bracket 156. The bracket 156 is fixed to a housing 157 which surrounds the gears 83 and 84. A lever 158 is fixedly mounted on the other end of the rock shaft 155 so that the lever 154, the rock shaft 155, and the lever 158 (Fig. 7) function as a bell crank lever. The arm 150 carries a stud 159 which supports an actuating roller 160 which is arranged in the path of a feed dog 161 which is adjustably supported by a T-slot 162 formed in the front edge of the table 16. A spring 163 is interposed between a stud 164 fixedly mounted on the housing 157 and a stud 165 which is fixedly mounted on the link 152. The spring 163 serves normally to move the link 152 in a direction toward the left (Fig. 5) so that an adjustable stop screw 166 carried by the pawl carrying member 146 is normally held against a fixed abutment 167 which is supported on the housing 157. When the table 16 moves toward the right (Figs. 1 and 2), the cam face on the dog 161 serves to depress the roller 160, thus rocking the shaft 155 and the arm 154 to move the link 152 toward the right (Fig. 5), which movement serves to rock the pawl carrying member 146 in a counterclockwise direction so that the pawl 148 turns the ratchet wheel 145 to produce a rotary movement of the feed screw 71 so as to cause an infeeding movement of the grinding wheel 25. When the table 16 moves toward the left so that the dog 161 rides out of contact with the roller 160, the released tension of the spring 163 serves to move the link 152 and the pawl carrying member 146 in a clockwise direction, during which movement the pawls 148 ride idly over the ratchet teeth on the ratchet wheel 145. By adjusting the position of the stop screw 166, the extent of oscillating movement of the pawl carrying member 146 may

be varied as desired so as to pick up the desired number of teeth on the ratchet wheel 145 each time the feed dog 161 moves into an operative position.

5

Table traversing mechanism

In order to grind a helical groove in a work piece, it is desirable to provide a suitable table traversing mechanism which is arranged so that the table traversing movement may be readily synchronized with the work rotation. In the preferred construction, as illustrated in the drawings, a rotatable lead screw 175 is supported underneath the table 16 by means of bearings 176 and 177 which are either formed integral with or fixedly mounted on the under surface of the table 16. The outer end of the lead screw 175 is provided with a sprocket 178 which is connected by a link chain 179 with a headstock mechanism to be hereinafter described. The lead screw 175 passes through a normally stationary rotatable nut 180. The nut 180 is contained within a casing 181 which is fixedly mounted to the base 15. The nut 180 is held against endwise movement by a pair of end thrust members 182 and 183 which are adjustably fixed in the ends of the casing 181. During the power traversing movement of the table 16, the nut 180 is held against rotation in a manner to be hereinafter described so that when the lead screw 175 is rotated through the nut 180, the table 16 together with the lead screw 175 will be moved endwise to traverse the work piece relative to the grinding wheel.

35

Hand traverse adjustment

In setting up the machine or in adjusting the table relative to the wheel, it is desirable to provide a suitable micrometer adjusting mechanism whereby the table 16 may be manually adjusted, accurately to position a work piece in the desired relationship with the grinding wheel 25 so that the grinding wheel may be readily aligned with the spiral path formed in the periphery of the work piece. The nut 180 is provided with an integral worm gear 184 (Fig. 16) which meshes with a worm 185. The worm 185 is mounted on the inner end of a rotatable shaft 186 which is journaled in a bearing 187 fixedly mounted relative to the base 15. The forward end of the shaft 186 is supported in bearings 188 and 189 formed in a housing 190 which is fixedly supported on the front of the machine base. A gear casing 191 is formed integral with the bracket 190. A gear 192 is mounted on the forward end of the shaft 186 and meshes with a gear 193 which is rotatably supported on a stud 194 carried by the housing 191. A manually operable hand wheel 195 is fixedly mounted to rotate the gear 193 when desired to transmit a rotary movement to the nut 180.

The hand wheel 195 is normally held stationary by means of a spring-pressed index stud 196 which is arranged to engage any one of a plurality of index holes 197 formed in a circular path in a cover plate 198 fastened to the housing 191. When it is desired to rotate the hand wheel 195, a knob 199 is pulled toward the operator to disengage the locking or index stud 196 from the apertures 197 and the hand wheel 195 may then be readily rotated as desired.

In order that the table may be precisely adjusted, the gear mechanism between the hand wheel 195 and the nut 180 is preferably such that the rotation of the hand wheel to pass the

75

indexing stud 196 from one hole to the next serves to advance or traverse the table 16 by a precise amount, for example .0005". The amount of advance between index holes may be varied as desired by varying the gear ratio between the hand wheel 195 and the nut 180. It will be readily apparent from the foregoing disclosure that a rotary movement of the screw 175 serves to transmit a longitudinal traversing movement of the table 16. When the table 16 is stationary, rotation or indexing of the hand wheel 195 serves to produce a rotary movement of the normally stationary nut 180 to impart a relative traversing movement between the table 16 and the screw 175 precisely to adjust the position of the work piece relative to the grinding wheel.

Work supporting and rotating mechanism

The work piece to be ground may, if desired, be supported by a head and footstock mechanism, such as is utilized in common practice in the old and well known cylindrical grinding machines. In the preferred construction, however, a work piece 205 is rotatably supported in a special fixture 206. The fixture 206 is supported by a transversely movable slide 207 which is adjustable transversely relative to the table 16 on a dovetailed slideway 208. A nut and screw mechanism (not shown) may be provided precisely to adjust the slide 207 and the fixture 206 transversely relative to the table 16 so as to align the axis of the work piece 205 into substantial alignment with a headstock spindle 209 which is rotatably supported in a headstock 210. A universal driving connection 211 is provided between the headstock spindle 209 and the end of the work piece 205 uniformly to rotate the work piece 205 even though its axis of rotation may be slightly out of line with the headstock spindle 209. The headstock spindle 209 is rotatably supported in bearings 212 and 213 which are fixedly mounted within the headstock 210.

To facilitate an efficient grinding operation, it is desirable that the work and wheel traverse relatively at a normal grinding speed while the work is rotated at a grinding speed, after which the wheel recedes to an inoperative or rearward position and the wheel and work piece are traversed longitudinally on the return stroke at a rapid rate to cut down the idle time. It is desirable that the grinding operation proceed while the work is traveling in one direction only since there is more or less backlash in the operating parts and it is necessary to return the work and wheel to an initial position and to take up all of the backlash before the wheel is brought into operative engagement with the work for the next grinding pass.

The headstock driving mechanism is arranged not only to drive the headstock spindle 209 but also synchronously to drive the lead screw 175 to traverse the table 16 so that the headstock spindle 209 and the lead screw 175 are at all times synchronously rotated. A driving motor 215 is mounted on the headstock 210. The motor 215 is provided with a pulley 216 which is connected by means of a multiple V-belt 217 with a pulley 218 mounted on the outer end of the rotatable shaft 219. The shaft 219 is rotatably supported in the headstock 210 in bearings 220 and 221. The shaft 219 supports a worm 222 which meshes with a worm gear 223 mounted on a transversely extending rotatable shaft 224. The shaft 224 is rotatably supported in bearings 75

225 and 226 which are fixedly mounted in the headstock 210.

In order to drive the headstock spindle 209 at a grinding speed on the operative stroke, the shaft 224 is provided with a left-hand worm 228 which meshes with a worm gear 229 which is rotatably mounted on a rotatable shaft 230 which is journaled in bearings 231 and 232 in the headstock 210. The side of the worm gear 229 is provided with clutch teeth 233 which are arranged to be engaged by clutch teeth on a slidably mounted clutch member 234 which is slidably keyed on the shaft 230 by means of a key 235. It will be readily apparent from the foregoing disclosure that when the clutch member 234 is moved toward the right (Fig. 9) so that the teeth on the member 234 engage the teeth 233 on the worm gear 229, any rotary motion of the worm gear 229 will be transmitted to rotate the shaft 230. The shaft 230 is provided with a driving sprocket 236 which is connected by means of a link chain 237 with a sprocket 238 which is keyed onto the headstock spindle 209 so that rotary motion of the shaft 230 will be transmitted to rotate the headstock spindle which in turn transmits a rotary movement to rotate the work piece 205.

In order to drive the feed screw 175 in timed relation with or synchronized with the headstock spindle 209, a suitable driving mechanism is provided comprising a sprocket 240 (Figs. 8 and 9) mounted on the end of the headstock spindle 209. The sprocket 240 is connected by means of a link chain 241 with a sprocket 242 (Figs. 8, 9 and 10) which is mounted on the outer end of a rotatable shaft 243. The shaft 243 is journaled in bearings 244 and 245 which are fixedly mounted in the headstock 210. A sprocket 246 is keyed to the shaft 243 and is connected by means of the link chain 179 with the lead screw 175 to rotate the lead screw 175 in synchronization with the headstock spindle 209.

An adjustably mounted rotatable idler 248 is mounted on a stud 249 which is carried by means of a bell crank lever 250. The bell crank lever 250 is pivotally supported on a stud 251 which is fixedly mounted on the headstock 210. An adjusting screw 252 which is cooperatively connected by means of a stud 253 with one end of the bell crank lever 250 serves to facilitate adjustment of the idler 248 to take up the slack in the link chain 241.

A rotatable idler 255 supported on a stud 256 which is fixedly mounted on an adjustable bracket 257 supported on the headstock 210 serves to take up the slack in the link driving chain 179 to facilitate synchronizing the rotation of the wheel spindle 209 with the table lead screw 175. The bracket 257 is provided with elongated slots 258 and 259. Clamping screws 260 and 261 (Fig. 10) pass through the elongated slots 258 and 259, respectively, and are screw threaded into the frame of the headstock 210 and serve to clamp the bracket 257 in adjusted position after the bracket and idler 255 have been moved to properly tension the driving chain 179.

To facilitate driving the lead screw rapidly in the reverse direction, a right-hand worm 265 (Figs. 8 and 11) is fixedly mounted on the shaft 224. The worm 265 meshes with a worm gear 266 which is rotatably mounted on the shaft 243. The worm gear 266 is provided with clutch teeth 267 which are arranged to engage clutch teeth formed on the slidably mounted clutch member 268. The clutch member 268 is slidably keyed on

the shaft 243. When the clutch member 268 is moved upwardly (Fig. 11) so that its clutch teeth engage the clutch teeth 267, the worm gear 266 will be clutched to rotate the shaft 243 at a comparatively fast speed. The rotation of the shaft 243 will transmit a rotary movement through the link chain 241 to rotate the headstock spindle 209 at a comparatively fast speed in the reverse direction. At the same time, the rapid rotation of the shaft 243 will be transmitted through the sprocket 246 and the link chain 179 to rotate the sprocket 178 and the lead screw 175 at a comparatively rapid rate in the reverse direction to traverse the table 16 through an idle or return stroke to its initial starting position.

The slideable clutch members 234 and 268 are preferably actuated by a common operating means so that one clutch is engaged while the other remains disengaged and vice versa. A vertically arranged rock shaft 270 is supported in a suitable elongated bearing 271 (Fig. 8) formed integral with the headstock frame 210. The lower end of the shaft 270 is provided with yoke-shaped arms 272 and 273 which support studs 274 and 275 which ride within a groove 276 formed in the clutch member 234. A pair of yoke arms 277 and 278 are formed integral therewith and are provided with studs 279 and 280, respectively, which are arranged to engage a groove 281 formed in the periphery of the clutch member 268. It will be readily apparent that when the shaft 270 is rocked in a clockwise direction (Fig. 11), the yoked arms 277 and 278, through the pins or studs 279 and 280, will shift the clutch member 268 upwardly to engage with the clutch teeth 267 formed on the worm gear 266 so as to rotate the headstock spindle 209 and also the table operating lead screw 175 in a reverse direction at a comparatively rapid rate which continues during the return stroke of the work supporting table 16. Similarly, when the shaft 270 is rocked in a counterclockwise direction (Fig. 11), the yoke arms 272 and 273 through the pins or studs 274 or 275, respectively, will shift the clutch member 234 upwardly (Fig. 11) to engage it with the teeth 233 formed integral with the gear 229 to rotate the headstock spindle 209 at a grinding speed and synchronously to rotate the table operating lead screw 175 to traverse the table 16 in synchronized relationship with the rotation of the work piece 205 at a normal grinding speed. At the same time the clutch 234 is thrown into engagement with the clutch teeth 233, the clutch member 268 is thrown out of engagement with the clutch teeth 267.

In order that the cycle of operation may be automatic, it is desirable to actuate the clutch shifting shaft 270 in timed relationship with the other moving parts of the machine. In the preferred form, a hydraulically operated actuating mechanism is provided comprising a fluid pressure cylinder 285 (Figs. 1, 3, 8 and 9) which is mounted on top of the headstock 210. A piston 286 (Figs. 3 and 9) is slidably mounted within the cylinder 285. A piston rod 287 is fixedly connected to the piston 286. The other end of the piston rod supports an adjustably positioned stud 288 (Fig. 9) which is connected by means of a lever 289 which is fixedly mounted on the upper end of the clutch shifting rock shaft 270.

As illustrated in the drawings, the clutch actuating cylinder 285 is preferably hydraulically connected with the wheel feed cylinder 93. A pipe 290 is connected between the valve chamber 106

in the feed cylinder 93 and a cylinder chamber 291 formed in the left-hand end of the cylinder 285 (Figs. 3 and 9) to cause the piston 286 to move toward the right, which movement serves to rock the shaft 270 in a clockwise direction (Fig. 11) to throw the clutch member 268 into engagement with the teeth 267 on the gear 266 to rotate the headstock spindle 209 and the lead screw 175 rapidly in a reverse direction to start the table traversing on its idle stroke to return the work piece to the initial position. The pipe 290 is arranged so that when the fluid under pressure flowing to the wheel feed cylinder 93 is reversed, the piston 94 will move rearwardly a sufficient distance to withdraw the wheel 25 from within the groove in the work piece before the piston 94 uncovers the pipe 290 to shift the clutch member 268 and start the return table movement. Similarly, when fluid under pressure is admitted through the passage or pipe 108 to initiate a forward feeding movement of the piston 94, fluid under pressure is also passed through a pipe 292, into a cylinder chamber 293 at the right-hand end of the cylinder 285, to cause the piston 286 to move toward the left (Figs. 3 and 9), which movement serves to rock the shaft 270 in a counterclockwise direction to throw the clutch member 234 into engagement with the clutch teeth 233 and to disengage the clutch member 268, thus traversing the table 16 at a normal grinding speed which is synchronized with the rotation of the headstock spindle 209 which also is rotating at the normal work speed for the given grinding operation.

The various moving parts of the machine are interlocked and controlled by an electrical control system. A pair of switches 295 and 296 (Fig. 3) contained within a housing 297 (Fig. 2) are supported by a bracket 298 which is in turn fixedly supported on the end of the dash pot frame 120. The switches 295 and 296 are arranged to be actuated by an adjustably mounted bracket 299 which is adjustably supported on a threaded end portion 300 of the piston rod 92. The bracket 299 supports a longitudinally extending member having a T-slot 301 formed therein which supports a pair of adjustably mounted dogs 302 and 303 (Figs. 2 and 12) which are arranged respectively to engage the lever arms 304 and 305 which are formed integrally with a hub member 306. The hub 306 is fixedly supported on a rock shaft 307 which serves simultaneously to actuate the switches 295 and 296. The switches 295 and 296 are connected and arranged so that one of the switches is closed while the other is opened. The switches 295 and 296 are arranged so that when the wheel slide is in a rearward position, the switch 295 is closed and the switch 296 opened. Similarly, when the wheel slide moves forward to position the grinding wheel 25 in an operating position, the switch 296 closes and the switch 295 opens.

The work and table driving motor 215 is preferably a variable speed, reversible type motor. This motor is controlled by means of a starter switch 310 illustrated diagrammatically in Fig. 3. The motor is controlled by two magnetic starter switches, namely a magnetic starter switch 311 for rotating the work in a normal grinding direction and traversing the table therewith. A second magnetic switch 312 is connected so as to rotate the motor and traverse the table in the reverse direction.

In the preferred construction, it is desirable

that a jogging mechanism be provided whereby the table 16 may be jogged longitudinally to accurately position the work piece in the desired relationship with the grinding wheel. A manually operable momentary contact jog switch 315 is connected in series with a limit switch 316 located adjacent to the right-hand end of the base 15. The limit switch 316 is in turn connected to actuate the forward magnetic switch 311 to jog the motor 215 so as to adjust the position of the table 16 longitudinally toward the right relative to the grinding wheel 25.

Similarly, a momentary contact jog button 317 is connected in series with a limit switch 318 which is connected to actuate the magnetic switch 312 to jog the motor 215 in the reverse direction so as to jog the table 16 toward the left to facilitate accurately positioning the table 16 longitudinally relative to the grinding wheel 25 in a direction toward the left. The jog buttons 315 and 317 are preferably interconnected with an automatic cycle control switch 320 so that when the switch 320 is set for an automatic grinding cycle, the jog buttons 315 and 317 are rendered inoperative. The limit switches 316 and 318 are arranged in the path of fixed dogs 321 and 322 on the table 16 which serve as safety devices to stop the traversing movement of the table 16 before either the bearing 176 or the bearing 177 moves into engagement with the housing 181 surrounding the nut 180.

A double contactor limit switch 323 is mounted on the front of the machine base. This switch is a normally closed switch and is arranged automatically to be opened by means of an adjustable table dog 324 when the table 16 moves to its left-hand end position at the end of the grinding operation. Similarly, a double contactor limit switch 325 is mounted on the front of the machine base and is arranged to be actuated by means of an adjustable table dog 326. The switch 325 contains a normally open contactor 327 and a normally closed contactor 328. When the dog 326 moves toward the right with the table 16 and actuates the switch 325, the contact 327 is closed and simultaneously therewith the contactor 328 is opened.

A start snap switch 330 is provided for initiating a starting of the grinding cycle. When the starting switch 330 is closed, the machine will continue to go through the cycle of operation and will then repeat the cycle until the starter snap switch 330 is actuated to open the circuit and stop the cycle of operation after it has completed its cycle.

The operation of the improved helix grinding machine will be readily apparent from the foregoing disclosure. Assuming all of the parts to have been previously adjusted and a new work piece 205 is in operating position on the supporting fixture 206 and the grinding wheel 25 is shown at its inoperative position where it stops at the end of a complete grinding cycle, the cycle of operation is started by actuation of the cycle control start switch 330 to close a circuit. In this position the slide 32 is in its rearmost or inoperative position and the closing of the cycle control switch 330 serves to actuate the magnetic starter switch 311 which through the starter control mechanism 310 serves to start the headstock motor 215 to traverse the table 16 longitudinally toward the right at a high speed. The high speed clutch is in operative engagement due to the fact that the slide 32 is in its rearmost position. The table 16 travels rapidly toward the right until the

table dog 326 actuates the limit switch 325 to close the switch 327 which serves through a magnetic switch 332 to energize the solenoid 111 which shifts the feed control valve 99 into its reverse position to initiate a forward feeding movement of the grinding wheel 25. At the same time the switch 327 closes to initiate a forward feeding movement, the switch 328 opens to open the magnetic switch 311 which serves through the starter control 310 to stop rotation of the head stock motor 215 which stops the rotation of the work piece 205 and also stops the longitudinal movement of the table 16.

When the solenoid 111 is energized and the valve 99 shifts upwardly to admit fluid under pressure through the pipe or passage 108 into the cylinder chamber 107 to initiate a forward movement of the piston 94, fluid under pressure is also passed through the pipe 292, into the cylinder chamber 293, to move the piston 286 toward the left which serves to rock the shaft 270 in a counterclockwise direction (Fig. 11) to throw the slow speed clutch member 234 into engagement with the teeth 233 so that the rotation of the motor 215 will be transmitted through the worm 228 and the worm gear 229 to rotate the head-stock spindle 209 and also the lead screw 175 at a normal grinding speed. When the spindle 209 and lead screw 175 are first rotated to start rotation of the work at a normal grinding speed and to start the table 16 traversing at a grinding speed in synchronism with the rotation of the work piece 205, the backlash in the driving mechanism is taken up so that when the grinding wheel 25 comes into contact with the work piece, the wheel will engage the work piece to grind the spiral path, as indicated. The traversing movement of the table 16 toward the left continues until the grinding wheel 25 grinds to the end of the spiral path on the work piece, at which point the adjustable table dog 324 opens the limit switch 323 which serves through the magnetic switch 332 to deenergize the wheel feed solenoid 111 to allow the released compression of the spring 110 to return the feed control valve 99 into the position illustrated in Fig. 3. At the same time, the opening of the limit switch 323 serves through the magnetic switch 311 to break a circuit which serves through the starter 310 to stop the rotation of the motor 215 which in turn stops the rotation of the work piece 205 and also the traversing movement of the table 16. The deenergizing of the solenoid 111 and the shifting of the valve 99 serves to admit fluid under pressure to move the piston 94 rearwardly into the position illustrated in Fig. 3, which movement serves to admit fluid under pressure through the pipe 290 into the cylinder chamber 291 to move the piston 286 toward the right (Fig. 3) to rock the shaft 270 in a clockwise direction (Fig. 11) to engage the high speed clutch ready for the next cycle of operation. This positions the wheel slide 27 and the grinding wheel 25 at the end of its cycle (as indicated in Fig. 3).

If the work piece 205 has been ground to the required extent, the cycle snap switch 330 must then be actuated to break the circuit, thus stopping the entire cycle of operation. Unless the starter switch 330 is actuated to break the circuit, the cycle of operation will be repeated indefinitely until the switch 330 is shifted to break the circuit, thus making several grinding passes of the work 205 across the face of the grinding wheel 25. It should be noted that the wheel 25 is in grinding contact with the work piece

205 only during the travel of the table 16 toward the left and that upon the return stroke of the table 16 toward the right at a rapid rate, the wheel 25 in its rearward or inoperative position thus makes an idle rapid pass of the work piece to position the work for the next grinding pass.

In the position of the switch 320, the circuit is closed for an automatic grinding cycle. In setting up the grinding machine for grinding a given work piece, it may be desirable to jog the table 16 longitudinally in either direction to adjust the position of the work piece 205 relative to the grinding wheel 25 so as to align the wheel with the helical path to be ground on the work piece. In such a case the switch 320 is actuated to open the upper switch contacter (Fig. 3) and to close the lower contacter. The closing of the lower contacter of switch 320 (Fig. 3) serves to render the jogging buttons 315 and 317 operative. In this position of the switch 320, if it is desired to jog the table 16 toward the right, the push button jog switch 315 is closed which serves through the magnetic switch 311 and the starter control mechanism 310 to start the motor 215 to move the table 16 toward the right. The push button 315 remains closed only so long as the operator holds it closed, thus enabling the operator to jog the table 16 by any desired amount to position the work piece relative to the grinding wheel 25. If it is desired to jog the table 16 toward the left, the jog button switch 317 is closed which serves through the magnetic switch 312 and the starter control mechanism 310 to start the motor 215 in the reverse direction to jog the table 16 toward the left the desired amount. The jog button 316 is closed only so long as the operator holds it closed, thus facilitating a manually controlled adjustment of the table 16 to position the work piece 205 relative to the grinding wheel 25. When it is desired to start the grinding operation, the switch 320 is again actuated to close the upper contacter and open the lower contacter so that the automatic cycle is then rendered effective.

The switch 295 (Fig. 3), which is actuated by the wheel feed mechanism, is shown closed and serves to close a circuit to shunt the limit switch 323 when it is in an open position, as shown in Fig. 3, so that the grinding operation may be started only when the grinding wheel is in its extreme rearward position.

The limit switch 296, which is also actuated in timed relation with the wheel feeding movement, serves to start rotation of the work piece 205 and a traversing movement of the table 16 only when the wheel slide 27 and the grinding wheel 25 are in a forward or operating position. It will be readily apparent from the foregoing description that when the table 16 moves to its extreme right-hand end position, the actuation of the limit switch 325 opens the magnetic switch 311 to stop the motor 215 which stops the work rotation and the longitudinal movement of the table 16. The wheel slide then moves forwardly and during the forward movement, as previously described, the switch 295 opens and the switch 296 closes to start the rotation of the motor 215 just before the wheel 25 moves into operative engagement with the spiral or helical groove in the work piece 205 to be ground.

It will thus be seen that there has been provided by this invention apparatus in which the various objects hereinabove set forth together with many thoroughly practical advantages are successfully achieved. As many possible embodi-

ments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a base, a rotatable grinding wheel, a transversely movable slide to support said wheel, means to feed said wheel transversely in either direction, a longitudinally traversable work supporting table, means to traverse said table longitudinally in either direction, a headstock including a rotatable spindle to rotate a work piece supported on said table, an electric motor on said headstock, driving connections including a clutch between said motor, spindle and table traversing mechanism to rotate said spindle and traverse the table in one direction at a normal grinding speed, driving connections including a clutch between the motor, spindle and table traversing mechanism to rotate said spindle and traverse the table in the opposite direction at a fast speed during an idle stroke of the table in the reverse direction, and means actuated by and in timed relation with the forward feeding movement of the wheel slide to shift the clutch to rotate the work and traverse the table at a normal grinding speed.
2. In a grinding machine having a base, a rotatable grinding wheel, a transversely movable slide to support said wheel, means to feed said wheel transversely in either direction, a longitudinally traversable work supporting table, means to traverse said table longitudinally in either direction, a headstock including a rotatable spindle to rotate a work piece supported on said table, an electric motor on said headstock, driving connections including a clutch between said motor, spindle and table traversing mechanism to rotate said spindle and traverse the table in one direction at a normal grinding speed, driving connections including a clutch between the motor, spindle and table traversing mechanism to rotate said spindle and traverse the table in the opposite direction at a fast speed during an idle stroke of the table in the reverse direction, and mechanism actuated by and in timed relation with the rearward movement of the wheel slide to shift the high speed clutch so as to rotate the spindle and traverse the table at a fast speed during an idle stroke.
3. In a grinding machine having a base, a rotatable grinding wheel, a transversely movable slide rotatably to support said wheel, means including a piston and cylinder to feed said slide transversely, a control valve therefor, a longitudinally traversable work supporting table, means to traverse said table longitudinally in either direction, a headstock including a rotatable headstock spindle to rotate a work piece supported on said table, an electric motor on said headstock, driving connections including a high speed clutch and a low speed clutch between said motor, spindle and table traversing mechanism to rotate said spindle and to traverse the table in the opposite direction at a fast speed during an idle stroke, and means including a piston and cylinder simultaneously to actuate both of said clutches in timed relation with the movement of said feed.
4. In a grinding machine having a base, a rotatable grinding wheel, a transversely movable slide rotatably to support said wheel, means including a piston and cylinder to feed said slide

transversely, a control valve therefor, a longitudinally traversable work supporting table, means to traverse said table longitudinally in either direction, a headstock including a rotatable headstock spindle to rotate a work piece supported on said table, an electric motor on said headstock, driving connections including a clutch between said motor, spindle and table traversing mechanism to rotate said spindle and to traverse the table at a normal grinding speed, driving connections including a clutch between the motor, spindle and table traversing mechanism to rotate the spindle and to traverse the table in the opposite direction at a fast speed during an idle stroke, means including a piston and cylinder simultaneously to actuate both of said clutches in timed relation with the movement of said feed, and fluid connections between the feed cylinder and clutch cylinder, whereby the high speed clutch is engaged when the grinding wheel is moved rearwardly to an inoperative position and the low speed clutch is engaged when the grinding wheel is moved toward an operative position.

5. In a grinding machine having a base, a rotatable grinding wheel, a transversely movable slide to support said wheel, means to feed said wheel slide transversely in either direction, a longitudinally traversable work supporting table, a headstock including a rotatable spindle, an electric motor on said headstock, driving connections including a clutch between said motor and spindle, and means actuated automatically by and in timed relation with the transverse movement of the wheel slide to actuate said clutch to start rotation of said spindle at a normal grinding speed when the wheel slide is moved to an operative position.

6. In a grinding machine having a base, a rotatable grinding wheel, a transversely movable slide to support said wheel, means including a piston and cylinder to feed said wheel slide transversely in either direction, a longitudinally traversable work supporting table, a headstock including a rotatable spindle, an electric motor on said headstock, driving connections including a clutch between said motor and spindle, means including a piston and cylinder to actuate said clutch, and fluid connections between said feed cylinder and said clutch cylinder whereby the clutch is automatically actuated to start rotation of the spindle at a normal grinding speed when fluid is admitted to the feed cylinder to move the grinding wheel into an operative position.

7. In a grinding machine having a base, a rotatable grinding wheel, a transversely movable slide rotatably to support said wheel, means including a piston and cylinder to feed said slide transversely, a control valve therefor, a headstock including a rotatable headstock spindle, an electric motor on said headstock, multi-speed driving connections between said motor and said spindle including a high speed and a low speed clutch, means including a fluid pressure operated piston and cylinder to actuate said clutches, and fluid pressure connections between said feed cylinder and said clutch cylinder whereby the high speed clutch is engaged when the wheel slide is moved to its rearmost position, and said low speed clutch is engaged when the wheel slide is in its forward or grinding position.

8. In a grinding machine having a rotatable grinding wheel, a transversely movable slide therefor, means to pivotally adjust said slide about a horizontal and a vertical axis to position the grinding wheel for grinding a helical groove,

means to feed said slide transversely, a longitudinally traversable work supporting table, means including a nut and screw mechanism to traverse said table, a headstock including a rotatable headstock spindle to rotate a work piece supported on said table, a reversible electric motor on said headstock, driving connections including a high and a low speed clutch between said motor, spindle and screw synchronously to rotate said spindle and screw either in one direction at a normal grinding speed or in the opposite direction at a fast speed during an idle stroke and means actuated by and in timed relation with the transverse movement of the slide to actuate said clutch.

9. In a grinding machine having a rotatable grinding wheel, a transversely movable slide therefor, means to feed said slide transversely, a longitudinally traversable work supporting table including a nut and lead screw to traverse said table, a headstock including a rotatable headstock spindle to rotate a work piece supported on said table, an electric motor on said headstock, driving connections including a high speed and a low speed clutch between said motor, spindle and lead screw to rotate said spindle and said screw either at a normal grinding speed or at a fast speed during an idle stroke and means actuated by and in timed relation with the transverse movement of said slide to actuate said clutch.

10. In a grinding machine having a rotatable grinding wheel, a transversely movable slide therefor, a longitudinally traversable work supporting table, means to feed said slide transversely, means including a nut and lead screw mechanism to traverse said table, a headstock including a rotatable headstock spindle to rotate a work piece on said table, an electric motor on said headstock, driving connections including a clutch between said motor, spindle and lead screw to rotate the lead screw and traverse the table in one direction at a normal grinding speed, driving connections including a clutch between the motor and the lead screw to rotate the lead screw in the opposite direction at a fast speed so as to traverse the table through a fast idle stroke in the reverse direction and means actuated by and in timed relation with the transverse movement of said slide to actuate said clutch.

11. In a grinding machine having a rotatable grinding wheel, a transversely movable slide therefor, means to feed said slide transversely, means to pivotally adjust said slide about a horizontal and a vertical axis to position the grinding wheel for grinding a helical groove, a longitudinally traversable supporting table, means including a nut and lead screw mechanism for traversing said table, a headstock including a rotatable headstock spindle to rotate a work

piece supported on said table, an electric motor on said headstock, driving connections including a high and a low speed clutch on said headstock between the motor, spindle and lead screw synchronously to rotate said spindle and screw either in one direction at a normal grinding speed or in the opposite direction at a fast speed during an idle stroke and means actuated by and in timed relation with the transverse movement of said slide automatically to actuate said clutch.

12. In a grinding machine having a base, a rotatable grinding wheel, a transversely movable slide therefor, means to feed said slide transversely, a longitudinally movable work support-

ing table on said base, a traversing mechanism for said table including a rotatable lead screw supported on the table, a normally stationary rotatable nut supported against endwise movement on the base, means including a manual indexing mechanism to rotate said nut, a headstock including a rotatable spindle to rotate a work piece supported on said table, an electric motor on said headstock, driving connections including a clutch between said motor, spindle and screw synchronously to rotate the work and

traverse it at a normal grinding speed as the table moves in one direction, driving connections including a clutch synchronously to rotate said spindle and screw in the reverse direction at a fast speed while the table is traversing in the reverse direction during an idle stroke and means automatically actuated by and in timed relation with the movement of said slide to actuate said clutch.

JOHN I. GARSIDE.
